UNITED STATES PATENT OFFICE.

JAMES O. HEADRICK AND JOHN M. WINFREY, OF HUMBLE, TEXAS.

WELL-BORING APPARATUS.

1,314,960.

Specification of Letters Patent. Patented Sept. 2, 1919.

Application filed June 20, 1918. Serial No. 240,958.

To all whom it may concern:

Be it known that we, JAMES O. HEADRICK and JOHN M. WINFREY, citizens of the United States, residing at Humble, in the county of 5 Harris and State of Texas, have invented certain new and useful Improvements in Well-Boring Apparatus, of which the following is a specification.

This invention relates to new and useful 10 improvements in a well boring apparatus.

The object of the invention is to provide a 15 device of the character described, through which a drill stem may be rotated, in drilling a well, and by means of which said stem may be held elevated, when it is desired to unscrew the joints thereof, in order to withdraw the stem from the bore.

In drilling by the rotary process, a drill 20 stem is employed, which is formed of sections, united by means of couplings.

To the lower end of this stem the drill bit is attached, and in drilling, the stem is rotated by any well known form of rotary. When it is desired to withdraw the stem 25 from the bore, the sections of the stem must be separated, for convenience in handling, and in accomplishing this work, the stem is elevated and held in elevated position while the sections above the rotary are 30 being unscrewed. When these sections are unscrewed, and disposed of, the pipe is again elevated, and the upper sections again unscrewed and so on until the stem is entirely withdrawn.

35 It is the object of this invention to provide an apparatus through which the stem may be rotated in drilling, and by means of which said stem may be held in elevated position, while being separated into sections 40 and disposed of, as hereinbefore explained.

With the above and other objects in view, the invention has particular relation to certain novel features of construction, operation and arrangement of parts, an example 45 of which is given in this specification and illustrated in the accompanying drawings wherein:-

Figure 1, is a plan view of the apparatus showing the pipe gripping device removed, 50 and

Fig. 2, is a side elevation thereof, shown partially in section.

Referring now more particularly to the drawings, wherein like numerals of refer-

ence designate similar parts in each of the 5 figures, the numeral 1, refers to a supporting framework, whereon the base plate 2 is mounted, said plate having a central opening 3, and surrounding said opening is an annular upstanding flange 4. Mounted 60 upon the base plate and surrounding said flange is the rotary table 5, and interposed between said plate and table are the anti-friction rollers 6, upon which the table operates. Said table is secured in position by 65 means of a ring-like nut 7, which is threaded into the upper end of the flange 4, and seats in a counter-sunk groove 8, in the table. The underside of the table is formed into a beveled gear face 9, which is in mesh 70 with the pinion 10, fixed upon the inner end of the drive shaft 11. Mounted upon the rotary table is a pipe gripping device as 12, of any desired form, which grips and rotates the stem 13, in drilling. The inner 75 wall of the annular flange 4 is provided with a plurality of vertically extending recesses 14, in which the respective dogs 15 are pivoted, at their lower ends. These dogs are held withdrawn into their respective recesses during drilling operations, by means of the annular sleeve 16, which fits up into the central opening 3, of the base plate. This sleeve is held in position by means of a plurality of set bolts as 17, which extend 80 through vertically extending slots 18, in the sleeve, and are anchored to the base plate. These slots permit a limited vertical movement of the sleeve 16 relative to the base plate. The numeral 19 refers to a trans- 90 verse shaft, which is rotatably mounted in suitable bearings, and extending therefrom are the rigid arms 20, which are spaced apart, and whose free ends are turned inwardly, and engage under the sleeve 16. 95 One end of this shaft is turned upward, forming the lever 21, and a link 22, is provided, one end of which is pivoted to the free end of said lever, and the other end of which is pivoted to the free end of the arm 20. 100 23, which is fixed to and projects upwardly from the shaft 24. This shaft is rotatably mounted in suitable bearings, and its outer end is formed into a foot pedal 25. When this pedal is depressed, it operates through 105 the mechanism just described to elevate the free end of the arm 20, which in turn elevates the sleeve 16, and the upper end there-

of, contacts against the dogs 15, to force them back into the recesses 14, where they are held during drilling operations. When it is desired to withdraw the stem, the pedal 5 25, is released, permitting the sleeve to descend, which in turn, permits the dogs to drop inwardly against the stem 13. The upper ends of these dogs have jaws, as 26, secured thereto, whose inner faces are serrated, and engage against the stem. When 10 it is desired to withdraw the stem it is pulled upwardly a distance so as to bring the upper sections thereof above the rotary, where they may be unscrewed. When the pipe is 15 released, the dogs immediately engage therewith, and hold it in elevated position, so that the upper sections may be unscrewed and disposed thereof. The stem is then again pulled upwardly, so as to bring the 20 other device to an accessible position and thereupon the dogs will again immediately grip the stem and prevent it from descending, while the exposed sections are being disposed of, and so on until the entire stem is 25 withdrawn.

What we claim is:

1. In a device of the character described, a base plate having an opening therethrough, to admit a drill stem, pipe engaging means anchored to said base plate and provided 30 to engage with a stem and hold the same elevated, and a sleeve arranged in the base plate opening and provided to engage with and hold said means withdrawn from the stem. 35

2. The combination with a suitable base, having a central opening, of a plurality of dogs pivotally secured to the base, a sleeve, fitted within said opening and means for actuating the sleeve against said dogs to hold them apart. 40

In testimony whereof we have signed our names to this specification in the presence of two subscribing witnesses.

JAMES O. HEADRICK.
JOHN M. WINFREY.
